UNITED STATES PATENT OFFICE

148,902

DESIGN FOR A PROVINCIAL STEP TABLE

Guido Alessandrini, Grand Rapids, Mich., assignor to Townsend Manufacturing Company, Zeeland, Mich., a corporation of Michigan

Application August 5, 1946, Serial No. 132,296

Term of patent 7 years

(Cl. D33—14)

To all whom it may concern:

Be it known that I, Guido Alessandrini, a citizen of the United States, residing at Grand Rapids, in the county of Kent and State of Michigan, have invented a new, original, and ornamental Design for Provincial Step Table, of which the following is a specification, reference being had to the accompanying drawing, forming part thereof.

Fig. 1 is a side elevation of the provincial step table showing the new design.

Fig. 2 is a front elevation of the same.

Fig. 3 is an opposite side elevation of the same.

Fig. 4 is a perspective view of the same.

The back of the design presents a substantially plain surface.

I claim:

The ornamental design for a provincial step table, substantially as shown and described.

GUIDO ALESSANDRINI.
